UNITED STATES PATENT OFFICE.

CHARLES H. GRANBERG, OF DOVER, NEW JERSEY.

LICENSE-NUMBER-DISPLAY DEVICE.

1,301,250.

Specification of Letters Patent. Patented Apr. 22, 1919.

Application filed April 16, 1915. Serial No. 21,721.

To all whom it may concern:

Be it known that I, CHARLES H. GRANBERG, a citizen of the United States, residing at Dover, in the county of Morris, State of New Jersey, have invented certain new and useful Improvements in License-Number-Display Devices; and I do hereby declare the following to be a full, clear, and exact description of the invention, such as will enable others skilled in the art to which it appertains to make and use the same.

This invention relates to devices for displaying the license numbers of automobiles.

The object of the invention resides in the provision of a device of the character named embodying an improved construction whereby the license number of an automobile can be displayed with equal clearness in either daylight or darkness.

With the above and other objects in view the invention consists in the details of construction and in the arrangement and combination of parts to be herein more fully described and particularly pointed out in the appended claims.

In describing the invention in detail reference will be had to the accompanying drawings wherein like characters of reference denote corresponding parts in the several views, and in which—

Figure 1 is a view in elevation of a license number display device constructed in accordance with the invention;

Fig. 2, a rear view of the device;

Fig. 3, a section on the line 3—3 of Fig. 1, and

Fig. 4, a section on the line 4—4 of Fig. 1.

Referring to the drawings the device is shown as comprising a casing A to which is secured L-shaped brackets 10 whereby the device may be conveniently secured to the rear of an automobile. The casing A is provided with a removable front B which comprises a frame 11,—having detachably secured therein an outer number panel 12 and an inner number panel 13. The outer number panel 12 is formed of suitable transparent material upon the inner side of which is applied an opaque material in such manner as to leave the numbers and letters of the license transparent. The inner number panel is formed preferably of white china through which rays of light can penetrate in a subdued manner. By this construction

it will be apparent that in daylight the numbers of the license will appear clear white and will be displayed with equal clearness in darkness when the interior of the casing A is illuminated. This illumination is effected through the medium of the usual tail lamp 14 which is secured to the casing A through the medium of bracket arms 15 attached to the rear of the casing A. The light of the lamp 14 is delivered into the casing A through an opening 16 in one end 55 of the casing. A reflector 17 is mounted in the casing A for the purpose of directing the light against the panels 12 and 13.

The reflector, as shown in the drawing, can be removed from the casing A through the open end 16 thereof, when the lamp 14 is removed from the casing, this end being flared as will be obvious, but said reflector is normally held within the casing through engagement with the lamp as illustrated in Fig. 3 of the drawing. The reflector has its end distant from the lamp curved toward the front of the casing and this curved end engages the closed end of the casing. The reflector is thus held immovable between this end of the closed casing and the lamp. It will be understood of course that this provision for the removal of the reflector permits of the cleaning of the latter without detaching the front B with resultant danger 80 of breaking the plates 12 and 13.

What is claimed is:—

1. A license number display device comprising a box-like casing open at its front and having a flared open end, a frame fitted on the open front and having transparent and translucent symbol sections carried thereby, a reflector removably fitted within the casing and having a flared portion engaging the flared open end of said casing and extractable through said open end, a bracket carried by the casing at the open end, and a lamp detachably fitted on the bracket and having a front flared and abutting the flared open end of the casing to hold the reflector within said casing, said lamp being arranged to direct its light into the casing through the open end of the latter and between the reflector and the front portion of the casing. 100

2. A license number display device comprising a box casing open at its front and having a flared open end, a frame fitted on

the open front and having transparent and translucent symbol sections carried thereby, a reflector removably fitted within the casing and having a flared portion engaging the flared open end of said casing and extractable through said open end, and illuminating means abutting the flared open end of the casing to hold the reflector within

the same and directing light through the open end of the latter.

In testimony whereof, I affix my signature, in the presence of two witnesses.

CHARLES H. GRANBERG.
